SPREADING AND SHADING WHEEL FOR SPARKLING LIQUID EMBROIDERY PAINT

Americus Emery Vuotto, Maywood, N.J., assignor to
Tri-Chem, Inc., Belleville, N.J., a corporation of Delaware

Filed Sept. 22, 1964, Ser. No. 81,833

Term of patent 14 years

(Cl. D9—2)

FIG. 1

FIG. 2

FIGURE 1 is a plan view of a spreading and shading wheel for sparkling liquid embroidery paint embodying my novel design; and

FIGURE 2 is a side view of this spreading and shading wheel.

I claim:

The ornamental design for a spreading and shading wheel for sparkling liquid embroidery paint, substantially as shown and described.
